UNITED STATES PATENT OFFICE.

THÉOPHILE PRESSARD, OF PARIS, FRANCE.

STEAM-GENERATOR.

SPECIFICATION forming part of Letters Patent No. 432,075, dated July 15, 1890.

Application filed May 22, 1889. Serial No. 311,665. (No model.) Patented in France September 6, 1888, No. 192,825, and in Belgium March 6, 1889, No. 85,298.

To all whom it may concern:

Be it known that I, THÉOPHILE PRESSARD, a citizen of the Republic of France, residing at Paris, France, have invented certain new and useful Improvements in Steam-Generators, (for which I have obtained patents in France, No. 192,825, dated September 6, 1888, and in Belgium, No. 85,298, dated March 6, 1889,) of which the following is a specification.

10 The present invention relates to improvements in multitubular steam-generators with removable tubes.

In the accompanying drawings, Figure 1 represents a vertical section of the tubular boiler. Fig. 2 represents a plan of the boiler, partly in section, on the line III IV of Fig. 1. Fig. 3 represents a front elevation of the same, half in section, on line I II of Fig. 1. Fig. 4 is a rear elevation. Fig. 5 represents the whole 15 boiler in vertical section. Fig. 6 represents a horizontal section of one of the tubular parts. Figs. 7 and 8 are details of modifications in the manner of joining the bolts and tubes.

20 The steam-generator consists, essentially, of, first, inclined vaporizing-tubes; second, chambers; third, a collector, and, fourth, a reservoir. Two tubes joined to one chamber form a vaporizing element and a vertically- 25 superposed number of chambers and tubes form a series. The vaporizing-tubes are of two different diameters, the tubes placed at the bottom in the open combustion-chamber and producing a considerably greater quantity of steam than those placed above them being of considerably greater diameter than those arranged above them for the purpose of facilitating the disengaging of the steam and the admission of the water which replaces that 30 transformed into steam. These larger tubes C are arranged in pairs, one tube exactly above the other, so that the lower one receives the full action of the fire, and in it is formed much more steam than in the one immediately 35 above, which is almost screened by the lower tube. From this arrangement and the inclined position of the tubes it follows that the steam formed in the lower tube passes directly into the collector B and is at once 40 placed by water, which descends from the reservoir through the collector B and the upper

tube of the pair or element. It may be said that the lower tube is the vaporizer and the upper one the preliminary water-heater, for the water is heated in the upper tube, but 45 vaporized in the lower one. The arrows a, Fig. 5, indicate the movement of the water, the arrows b that of the steam, and the arrows c that of what little steam is generated in the upper tube of each pair. To obtain 50 the same results in the upper tubes F, these latter are arranged quincuncial, Fig. 5, and although this arrangement distributes the heat more equally to the tubes those situated at the lower part of each element will always 55 be more heated than the upper tubes. This arrangement in quincunx has for result to better cool the gases by obliging them to circulate in zigzag, and consequently to come in contact with all vaporizing-surfaces. The upper tubes may, however, if desired, be arranged vertically above the lower ones instead of the elements being arranged in quincunx. 60

The elements consisting of the big tubes 65 being those which produce the most steam are also those which produce the most deposit, and for the purpose of keeping these tubes constantly clean the joining chambers D of these tubes are so constructed as to be 70 provided with a chamber for the deposit. This deposit is removed under pressure by means of suitable valves E, Fig. 5. The inclined position of the tubes and difference in 75 the density of the two fluids in the different tubes in consequence of the difference in the temperature produce a circulation of the water sufficiently rapid to carry with it the deposit produced by the vaporization of the water. When the water and the steam arrive in the 80 collector B, they have to change their direction, and it is at this moment that the deposit can fall to the ground—i. e., to the bottom of the collector B, from whence it is removed by 85 means of suitable openings V. 90

The feed-water, which is injected into the rear end of the reservoir A above the level of the water therein, will be cleared of the greatest part of its calcium salts, which it contains in solution, by means of high temperature. 95 In this manner it arrives hot and nearly pure 100 in the vaporizing-tubes, where the little de-

posit which it still contains in solution is separated by the vaporization, and is drawn into the collector B by the force of the circulating current.

5 The dome or cupola from which the steam is taken is placed as far as possible from the upper opening of the collector B—*i. e.*, from the inlet of the steam into the reservoir A—so that it may entirely free itself of the water 10 which it might take with it. To further insure the steam being dry, a drier H, receiving the steam from the reservoir by means of the tube I, is placed on the top of the generator, so that the products of combustion must 15 come in contact with it during their passage to the chimney. From the drier the steam passes to the outlet-valve J.

To obtain the greatest possible utilization 20 of the fuel, the series of tubes is divided into two by a vertical transverse partition K, the front part being the larger and situated directly above the furnace. A screen L is placed on the upper tubes, so that the heat must pass to the front and oblige the gases to 25 pass along the drier H and heat the under side of the reservoir A. The gases then descend behind the partition K through the second or smaller part to the flue leading to the chimney. The arrows, Fig. 1, show the 30 passage of the gases.

To render all the tubes quickly removable, each is provided at its rear end—*i. e.*, at the collector end—with a forked bolt n, riveted to the tube and passing partly through the 35 collector B, the rear end of the collector serving as the support for the nut of the forked screw-bolt n. At the front end the tubes are provided with bolts having plates m, by means of which they are riveted to the tubes, and 40 which pass also through the joining chambers D and G.

To facilitate the mounting of the forked bolts on the tubes, plain bolts may be used, traversed by the rivets, and flat, so as to avoid 45 any resistance for the water in this narrower part. These bolts are arranged in such a manner that it will be easy to examine the tubes and that the joining chamber G can be provided with autoclave plugs or doors, thus 50 avoiding all possible danger of accidents which exists in other generators where the joints of the plugs are under the influence of the dilatation of the tubes. The tapered ends of the tubes are jointed by power, without any 55 cement, and the dry metallic joint thus obtained is absolutely tight. To remove a tube from the collector or the boxes, it suffices to give a blow with the hammer on the bolt, the nuts having been previously removed.

60 The above-described apparatus is fitted with the usual parts, such as a metallic casing M and the masonry, which serve as the base for the whole apparatus. Doors N in the casing M permit of the examination of the 65 joints of the tubes and the cleaning thereof. The furnace O and the ash-pit P are built

partly of refractory bricks Q and partly of ordinary bricks R. S is the flue leading to the chimney.

I claim—

1. In a steam-boiler, the combination, with a 70 collector, of a vertical series of inclined tubes communicating therewith at the upper end, the lower tubes of said series being of large diameter and the upper tubes successively of relatively smaller diameter, whereby the degree of heat imparted to the water contained in the tubes is uniform, substantially as described.

2. In a steam-boiler, the combination, with a 80 collector, of a series of pairs of inclined tubes communicating therewith at the upper ends, with communications between the tubes of each pair at the lower ends, said pairs of tubes being of larger diameter at the bottom and 85 successively of relatively smaller diameter at the top of the series, substantially as and for the purpose set forth.

3. In a steam-boiler, the combination, with a 90 collector, of a series of pairs of inclined tubes communicating therewith at the upper ends, with communications between each pair at the lower ends, the lower tubes of each pair being of larger diameter than the upper tubes of the same pair, and the tubes of the whole 95 series of pairs being of successively larger diameter toward the bottom of the series, substantially as described.

4. In a steam-boiler, the combination, with a 100 collector, of a series of pairs of inclined tubes communicating therewith at the upper ends and a communication between the tubes of each pair at the bottom, the tubes being arranged in quincuncial order, substantially as and for the purpose specified.

5. In a steam-boiler, the combination, with the 105 collector and the tubes communicating therewith, of the fastening-bolts having the forked ends riveted to the tubes and the screw-threaded end passing through the collector, substantially as described.

6. In a steam-boiler, the combination, with a 110 collector and a tube or tubes communicating therewith, of bolts for holding the same in position, having one end riveted to the tube 115 and the opposite screw-threaded end passing through the collector and provided with a nut, substantially as described.

7. In a steam-boiler, the combination, with a 120 collector and a tube or tubes communicating therewith, of flattened bolts having one end riveted to the tube and the opposite end screw-threaded and provided with a nut outside of the collector, substantially as described.

In testimony whereof I have hereto set my 125 hand in the presence of the two subscribing witnesses.

THÉOPHILE PRESSARD.
